UNITED STATES PATENT OFFICE.

ANDREW A. S. BURNS, OF MONTREAL, QUEBEC, CANADA.

DEVICE FOR CORRECTING DEFORMITIES OF THE FEET.

1,220,724.

Specification of Letters Patent. Patented Mar. 27, 1917.

Application filed October 21, 1915. Serial No. 57,217.

To all whom it may concern:

Be it known that I, ANDREW ARTHUR STANLEY BURNS, a subject of the King of Great Britain, residing in the city of Montreal, Province of Quebec, Dominion of Canada, have invented certain new and useful Improvements in Devices for Correcting Deformities of the Feet, and I do hereby declare that the following is a full, clear, and exact description thereof.

My invention relates more particularly to devices for the correction of deformities of the arch of the foot, and it has for its object to provide a support which can be readily made to conform to the affected part and retain the form.

To this end the invention may be said to consist of a strip of vulcanite attached to a sheet of flexible material such as wire gauze, or used alone, the vulcanite being preferably in the form of a comparatively thin sheet and the gauze being of relative rigidity in comparison with the less rigid vulcanite. Satisfactory results may be obtained by holding the strip to a form during vulcanization. Another method is to vulcanize the strip before forming it then when about to be used heat it thereby softening it and then form it while soft, and finally allow it to cool and reharden.

My improved device may be used as a combined arch support and stiffener for the shank of a shoe or it may be incorporated in a bandage, stocking or sock for use as an arch support only.

For full comprehension, however, of my invention reference must be had to the accompanying drawings forming a part of this specification in which similar reference characters indicate the same parts, and wherein:

Figure 1 is a plan view of the sole of a shoe with my improved device in use as a combined arch support and shank stiffener;

Fig. 2 is a longitudinal sectional view taken on line A B Fig. 1;

Fig. 3 is a side elevation of an ankle bandage having my improved device incorporated therein and serving as an arch support only.

Fig. 4 is a detail plan view of a portion of an ankle bandage with my improved device incorporated therein.

In carrying out my invention I press substantially pure unvulcanized rubber through the gauze 3 in such a way that it will present at either side thereof a film-like

coating preferably covering sufficient only of the gauze to present a combined shank-stiffener 5 and arch support 6 or either one. The article thus produced is then vulcanized.

When in use as a combined shank-stiffener and arch support as illustrated in Figs. 1 and 2 the gauze is extended to the edges of the shoe and stitched thereto, an insole being placed in the shoe over the stiffener and support. When in use as an arch support only it is attached to a bandage, stocking or sock as illustrated in Figs. 3 and 4 and is provided with a lateral convex portion 6 adapted to fit the arch of the foot.

Articles of this nature may be manufactured individually or in a large sheet containing a plurality of the arch supports, the sheet being subsequently divided into the individual devices of suitable dimensions to be incorporated in the shank and arch-portion or either one alone, of a boot, shoe or other article of footwear.

In order to obtain the best results my improved stiffener is manufactured as follows:

A comparatively large sheet of gauze of relative rigidity has placed upon its opposite sides a number of pairs of thin pieces of crude rubber of the shape required for individual or combined shank-stiffeners and arch supports. The corresponding sides of the pieces of each pair are then treated with cement or otherwise to impart a local viscous nature, and they are located in proper positions to cause those of each pair to register, and suitably spaced to permit the sheet to be divided and allow a sufficient margin of gauze to each rubber member for it to be stitched or otherwise fastened in place. This sheet is then passed between calender rolls or otherwise subjected to a sufficient degree of heat and pressure to cause the rubber to enter from opposite sides into interstices of the gauze and become merged in a single sheet, with the gauze embedded in it. The large sheet thus produced is then vulcanized after which it is cut and the shank-stiffeners or arch supports are ready for use.

The advantage of my vulcanite shank-stiffener or arch support is that it possesses the qualities of both support and cushion, the gauze being of just sufficient rigidity to prevent the vulcanite collapsing. With the metal devices heretofore used, however thin and resilient they were made and suitable for practical use, the inherent hardness ren-

dered them harsh and abrasive with consequent injury to the foot of the wearer.

Another advantage is found in the method by which I produce my stiffener and support. The fact that the device is vulcanite permits of its being manufactured by rubber factories in large quantities for the footwear trade, and formed to meet the specific needs of the different cases of deformity of the shank or arch by the footwear trader who heats and thereby softens it and forms it upon a last of the customer's deformed foot, then when sufficiently cooled and reset he removes it from the last to facilitate rehardening.

In applying my vulcanite stiffener-support thus formed it is stitched cemented or otherwise fastened between the insole and outsole, the gauze affording means for fas-

tening it in place and offering no obstruction to the stitching.

What I claim is as follows:

1. The combination with the shank of a shoe, of a vulcanite arch-support, and means for attaching the same to the shoe, such means consisting of wire gauze incorporated with the support.

2. An orthopedic vulcanite arch-support consisting of a sheet of wire gauze and layers of vulcanite on opposite sides of said gauze.

In testimony whereof I have signed my name to this specification in the presence of two witnesses.

ANDREW A. S. BURNS.
